UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

BUTTON-SEWING MACHINE.

Application filed April 21, 1923. Serial No. 633,625.

This invention relates to machines for sewing on buttons. As hitherto constructed the thread has been passed through the goods beneath each button thread hole at substantially the same point at each stitch. This causes the goods to be materially weakened and the attachment for the button to be insecure, in many instances the button being torn out of the goods while the threads are intact, causing a hole to be made therein.

According to the present invention the stitches through each hole of the button may be distributed over an extended area of the goods so that they have a better grip thereon and are not liable to be torn out and cause holes to be left in the goods.

A further feature of the invention relates to means adjustable to sew a two hole button with the same stitch in the goods as for a four hole button.

Still another feature of the invention relates to mechanism by which the machine may be adjusted for sewing either two or four hole buttons.

The invention also contemplates the employment of one or more work-engaging elements carried by the button clamp and movable therewith toward and from the work to clamp and release it on the work plate, said elements however being movable relative to the button clamp with the work as it is moved by the work plate. Interference with the proper movement of the work due to the pressure of the button clamp thereon is thus avoided.

For a more complete understanding of this invention, together with valuable features and advantageous details and combinations of the parts, reference may be had to the accompanying drawings in which

Figure 1 is a side elevation of the machine.

Figure 2 is a similar view showing a cover plate removed.

Figure 3 is a front elevation of the needle bar and casing.

Figure 4 is a horizontal section partly broken away on line 4—4 of Figure 2.

Figure 5 is an inverted plan of the machine head and mechanism carried thereby.

Figure 6 is a detail section on line 6—6 of Figure 4.

Figure 7 is an inverted plan of the thread deflector mechanism.

Figure 8 is a detail section on line 8—8 of Figure 6.

Figure 9 is a vertical section on line 9—9 of Figure 2.

Figure 10 is a fragmentary vertical section on line 10—10 of Figure 4.

Figure 11 is a fragmentary plan of the outer end of a button clamp.

Figure 12 is an end elevation thereof.

Figure 13 is a fragmentary side elevation of one of the clamping elements.

Figure 14 is a fragmentary rear elevation of the same.

Figures 15, 16, and 17 are fragmentary front, side and rear elevations, respectively, of a clamping element showing a modification.

Figure 18 is a view similar to Figure 10 showing parts in different positions.

Figure 19 is a section on line 19—19 of Figure 18.

Figure 20 is a fragmentary inverted plan of a cover plate.

Figure 21 is a perspective view of a connecting pin.

Figure 22 is an enlarged development of the cloth plate cam.

Figure 23 is a plan of a four hole button as sewed in position.

Figure 24 is a section on line 24—24 of Figure 23.

Figures 25 and 26 are views similar to Figures 23 and 24 but showing a two hole button.

Figure 27 shows the appearance of the stitch for both the four hole and two hole buttons on the back face of the cloth.

Referring more particularly to Figures 1 and 2, at 1 is indicated a substantially rectangular hollow supporting frame to which is hinged the machine head 2. This head is formed with a forwardly extending shelf or table portion 3 on which the work is supported, as will later appear, and extending upwardly from the rear of the portion 2 is a hollow post 4 having a forwardly extending arm 5 for supporting the needle guide bar housing 6, this housing being positioned above the table portion 3 in the usual manner.

The button to be sewed is carried by a button clamp indicated at 7 which may be of any suitable type, but which as herein illustrated is of the construction more fully shown, described and claimed in the application for patent of Harold W. Morris, Serial Number 643,897, filed June 7, 1923. The button is held between these clamping

elements 15 and 17, the holes in the button being arranged in one or more rows positioned transversely of the machine.

The button clamp is designed to support 5 the button and hold it to the upper face of the work which is carried by a cloth plate 60 (see especially Figures 1, 2, 4 and 6). This cloth plate is slidable lengthwise over the upper face of a throat plate 61 and over 10 a plate 62 forming the rearward continuation of the throat plate and which together form the top portion of the table 3. The upper face of the work plate 60 is serrated as at 63 (see Figures 4 and 6) so that work 15 pressed thereon will be carried beneath the button clamp as the work plate is moved lengthwise substantially parallel to the face of the work. The lower faces of the clamping elements which are formed as work 20 en- gaging feet 15 and 17 of the button clamp may be smooth so that the work may pass readily therebeneath while the button is held by the clamps, or the clamp may be provided with work-engaging elements movable 25 with the work and relative to the clamp as shown in Figures 11 to 17.

Referring first to Figure 11 to 14 inclusive, the button clamp 7 is shown as provided with a pair of oppositely facing jaws 10 pivoted 30 at their rear ends to a supporting plate 12, these jaws being downwardly turned to form work-engaging feet. A spring plate 15 holds the button in position relative to each foot. A third button clamp element 17 co- 35 operates with the elements 10 to clamp the button, all these elements being releasable from the button in the manner shown more particularly in the Morris application above referred to, by moving rearwardly the end 40 of a finger lever 44 pivoted on a screw 45 fixed to the plate 12.

Each of the elements 10, as shown in these figures, has fixed to its rear face at 50 above its lower end, the upper end of leaf spring 45 51 whose lower end is forwardly turned as at 52 and extends beneath the lower end of the corresponding element 10. The lower face of this end portion 52 engages the upper face of the work when the clamp is depressed, 50 and as the cloth plate moves lengthwise carrying the work therewith, the portion 52 of the spring may move with the cloth and independently of the button clamp, the upper portion 55 of the spring flexing to permit this action and acting to return the portion 52 to its normal position relative to the foot element as soon as the work is moved back or the button clamp is raised.

In Figures 15 to 17 the work engaging ele- 60 ment is shown as a slide 53 seated in a dovetail slot 54 arranged lengthwise of the cloth plate in the lower face of each clamping foot, this slide being urged into a predetermined position relative to its foot by a spring wire 65 55 having its lower end forwardly turned

and engaging in a perforation 56 in the rear end of the slide and its upper end made fast to the rear face of the foot element as by a screw 57. This slide may move rearwardly with the work, the spring wire 55 flexing to permit this action and acting to return the slide to its normal position when the work is returned or the clamp is lifted.

At its rear end the work plate 60 is made fast as by screws 64 to the forward end of a 75 slide 65 (see Figures 4, 10 and 18) which is mounted to slide in a guideway 65' (Figure 19) on the frame portion 2 in alinement with the platform 3. This slide 65 has fixed thereto, as shown in Figures 10 and 18, an arm 66 80 to which is pivoted by a horizontal pivot 67 an extension 68. This extension 68 has a hole 69 therethrough which may be brought into registry with a mating hole in the end of the arm 66 so that through these mating holes may be passed a pin 70 by which means the arm 66 and its extension are held in alinement. By removing the pin 70, the extension 68 may be raised upwardly and the pin 70 90 may then be placed in position within the perforations in the arm 66 and beneath a notch 68' in the lower edge of the extension whereby the rear end of the extension is held elevated. The end of this extension carries a cam follower 71 having a shank 72 threaded in the extension 68 and against the upper end of which bears the lower end of a screw 73 in axial alinement therewith by which the follower is axially adjustable and when the extension is in alinement with the arm this 100 cam follower engages in a cam groove 74 of a cam disk 75. This cam disk is fixed to rotate with a vertical shaft 76 extending upwardly and journaled within bearings 77 extending rearwardly from the forward wall 105 of the frame post 4. Above the cam 75 shaft 76 has fixed thereto a worm gear 80 (shown dotted in Figures 4 and 5) with which meshes a worm 81 on a horizontal main drive shaft 82 journaled in the head 2 of the machine and extending rearwardly therefrom where it is provided with any suitable drive mechanism 260. The cam groove 74 is so cut, as shown for example in Figure 4, that the slide 65 and consequently the cloth plate 110 when the follower 71 is in engagement therewith, is given a forward and backward motion between the formation of the various stitches and controls the distribution of the stitches in the goods supported on the cloth plate. When the cam follower 71 is out of engagement with the cam groove 74 the motion of the cloth plate may be controlled by 115 other means.

As shown such other means comprises a cam 85 also fixed to the shaft 76 and having a cam groove 86 on its lower face. Both cams 75 and 85, as shown in Figures 4 and 5, are angularly adjustable relative to the shaft 76, being fixed to a collar 90 pinned to the shaft, by means of screws 91 passing 120 125 130

through slots 92 therein and threaded in this collar. The cam groove 86 has riding therein as shown in Figure 5, a follower 95 carried at the free end of an arm 96 fixed to a vertically extending shaft 97. This shaft 97 has fixed at its upper end an arm 98 (Figures 4, 10 and 18) having a longitudinal guideway 99 in its upper face. Overlying this arm 98 is a slide 100 guided for movement parallel to the slide 65 and in contact with the upper face thereof by means of a pair of guides 101 overlying the slide 65. The rear end of this slide 100 is laterally extended as shown at 102 and is slotted at 102' to receive a stud 103 having a projection 104 from its headed lower end riding within the guideway 99 of the arm 98. The head of this stud rides within the grooved lower face of the portion 102 and on the threaded portion of the stud extending above the portion 102 is positioned a tightening nut 105. With this construction rocking motion imparted to the rock shaft 97 by means of the engagement of the follower 95 in the cam groove 86 causes an oscillatory movement of the arm 98. This motion is imparted to the slide 100, the amplitude of this motion being adjustable by setting the stud 103 in the desired position longitudinally of the slot 102'. This slide 100 may be connected to the slide 65 when the extension 68 of the arm 66 is disconnected from the upper cam 75. For this purpose a pin shown detached in Figure 21 at 110 is journaled within an opening in the forward end of the slide 100 within a depressed portion 111, this portion having adjacent to the pin 110 an inclined face 112 (see Figure 4). The pin 110 is provided with a laterally extending rod 113 forming a handle by which it may be turned and the rear end 114 of this rod is adapted to pass over the inclined face 112 so as to raise the pin 110 upwardly into the position shown in Figure 10. By turning the pin so that the portion 114 rides off the inclined portion 112, the pin may be depressed so that its lower end projects through the slide 100 and into a mating opening 120 in the slide 65, this position of the parts being indicated in Figure 18. In order to insure that this pin engages in the opening 120 of the slide 65, a spring 121 is shown as seated in a socket 122 in the upper end of the pin 110, this spring reacting against the lower face of a socket portion 123 formed in a cover plate 124 which overlies the slides 100 and 65 and is provided with a cut-away portion 125 (Figure 4) at its rear end through which the nut 105 projects so that its adjusting movement is not hindered. This plate 124, as shown in Figures 2 and 4, extends substantially the full width of the machine head 2. The forward edge of the plate 124 may be cut away, as indicated at 127, in order to permit access to be had to the rod 113. It may now be seen that the work plate

may be selectively connected to be given a forward and rearward motion by either of the cams 75 and 85.

The slide 100 may also have another function which is to move the button clamp when four hole buttons are being sewed to enable the stitching to take place between both pairs of holes positioned longitudinally of the machine. For this purpose the rear end of the slide 100 is provided with a pair of spaced ears 130 (Figure 4) between which extends the lower rear end of an L-shaped arm 131 (Figures 1, 2, 10 and 18), the forward end of which as at 132 is adjustably attached to the plate 12 of the button clamp as by means of screws 133 engaging slots 134 in the arm 131 and threaded in the plate 12. These screws 133 also serve to attach to the button clamp a plate 135 having at one end an upwardly extending ear 136 to which a chain 137 may be attached by which the button clamp may be raised upwardly from the cloth plate. The button clamp is normally urged downwardly toward the cloth plate in order to clamp work against the cloth plate by means of a leaf spring 138 fixed at its rear downwardly turned end 139 to the forward portion of the frame post 4, its forward end engaging the upper face of the plate 135. The rear end of the arm 131 may be pivotally connected to the ears 130 by means of a pivot pin 140 passing through mating perforations therein, the rear end of the arm 131 being provided with spaced perforated bosses 141 for this purpose. Extending between these bosses is a lug 142 fixed to the forward face of the frame post 4 which acts to prevent lateral lost motion of the arm 131 as it pivots about the pin 140. When the pin 140 is in position it is evident that the button clamp will be carried forwardly and backwardly with the forward and backward movement of the slide 100, the cam 85 for actuating the slide being so formed as to give the requisite forward and backward movement during the sewing operation to change the position of the button so that the needle passes through the forward and rearward pairs of holes of a four hole button. The extent of motion of this button clamp for this purpose is, of course, adjusted by changing the position of the stud 103. When it is desired to sew through a two hole button, the pin 140 is withdrawn from the ears 130 and 141 so as to disconnect the arm 131 from the slide 100. The pin is then passed through perforations 143 in the arm 131 and through a mating perforation 144 of the lug 142. By this means the forward and rearward motion of the button clamp is prevented but pivotal motion for permitting the button clamp to be moved toward and from the work plate is permitted. The chain 137 for raising the button clamp is connected to a

screw 146 (Figure 2) fixed to the end of an arm 147 made fast to a rock shaft 148 which may be rocked by a treadle (not shown) connected to a finger 156 projecting therefrom. 5 The rock shaft is normally held in position to permit the button clamp to engage the work by a coil spring 151 coiled about the rock shaft and having its ends engaging a fixed bearing 149 for the shaft, and a collar 10 152 fixed thereto.

The needle bar 173 (Figures 1, 2, 3, and 9) is designed to be given lengthwise strokes toward and from a looper mechanism housed within the frame portion 3 and it is also 15 given lateral motion to cause successive sewing strokes to pass through alternate holes of the button spaced laterally of the machine. This may be accomplished by any 20 suitable means but as herein shown the needle bar is swung laterally about a pivot according to the construction more fully shown, described and claimed in the application for 25 patent of Harold W. Morris, Serial Number 643,897, filed June 7, 1923. It is sufficient 30 for an understanding of the present invention to state that the needle bar is slidable through a sleeve 172 pivoted at 171 to the needle bar housing, and is given its sewing and retracting strokes by a crank arm 187 35 and link 188 from a rock shaft 185 actuated from the main drive shaft 82 of the machine by an eccentric 193 (Figures 4 and 5), a connecting rod 191 and an arm 190 fixed to the rock shaft, and that its lateral motion is 40 effected by a lever 197 adjustably fulcrumed at 201 and having at its forward end a sleeve 192 through which the needle bar passes, and at its rear end a cam follower 222 riding in a groove in a cam 220 fixed to the 45 upper end of the shaft 76. The path defined by this cam groove is so shaped that the needle passes alternately from side to side until the desired number of stitches have been made and then passes twice in 50 succession through the same hole to knot the thread. The machine is then stopped automatically and on raising the button clamp the thread breaks at the knot. The looper is shown at 230 and is carried by a rotary 55 shaft 232 driven by intermeshing gears 235 and 236 from the main shaft 82. A loop deflector finger 231 (Figures 6 and 7) is also employed to cooperate with the looper to properly position the loop of thread from the needle in the usual manner.

A button having been inserted in the button clamp with the holes arranged in line laterally of the machine, and work having been placed on the cloth plate, the button clamp 60 is allowed to bring the button down against the work whereupon the sewing of the button may be initiated through the drive mechanism. The needle then acts to pass through a pair of holes laterally of the machine alternately by the action of the cam 220. If a

two hole button is being operated upon the button clamp is given no motion lengthwise of the work arm 3, but if a four hole button is being sewed, it is given such motion during the sewing operation in order that both sets 70 or pairs of holes may have stitches passed therethrough. The relative motion of the needle and work causes the stitches to lie in substantially parallel lines on the work. If the work plate is moved by the cam 85 these 75 lines of stitches are arranged in two parallel groups, the work being pierced at four points to form the appearance on the lower face of the work shown at *a* in Figure 27. If the cam 75 is used to actuate the work plate, the 80 lines of stitches may be distributed laterally of these lengths, as shown at *b* in Figure 27. By reference to Figures 23 to 26 it will be seen that the stitches passing through each pair of holes in the button are spread in the 85 work in a direction transverse to a line joining the pair of holes. The cam 75 may, if desired, have its path shaped as indicated diagrammatically in Figure 22 in which after the first stroke of the needle in one of the forward pairs of button holes, the work is given a backward thrust so that the end of the thread becomes locked between the button and the top face of the work, this being shown at *e*. The work is then progressively moved 90 between stitches by successive increments, bringing different portions of the work successively in line with the holes in the button, until it reaches the point *f*. At about this point the button clamp moves to present the rear holes of the button (if a four hole button) to the needle and the work moves back to the point *g*. If a two hole button is being sewed the button remains stationary. The work then moves forward progressively to the point *h* at which time if desired, two needle strokes for the same hole may be made and the machine be stopped in the manner disclosed in the patent application of Raymond L. Plumley, Serial Number 655,279, filed August 2, 1923, for button sewing machines. If 95 desired the machine may continue its motion, the work being moved back sharply to the point *j* and then progressively moved forward by successive increments to the point *k* 100 at which time the cam 220 has completed its revolution, the final knotting stroke takes place and the machine stops at *l*. After the machine stops the operator depresses the treadle to raise the button clamp from the cloth plate which causes the thread to break at the knot and the work may then be disengaged by merely releasing the button from the button clamp.

I claim:

1. In a machine of the class described, a button carrier, a work holder, sewing instrumentalities for sewing a button carried by said carrier to work held by said holder, and means for relatively moving said carrier,

- holder and instrumentalities by successive increments during the sewing operation whereby a plurality of stitches passed through each of the holes in said button engage the work 5 at points spread along a line therein.
2. In a machine of the class described, means for holding a button and work in position to fasten the button to the work, sewing instrumentalities including a needle for 10 sewing the button to the work, means for causing the needle to pass through two holes in the button in alternation while the button is held stationary, and means for moving the work by successive increments relatively to the button between successive passes of the needle therethrough to cause stitches passing through the same hole in the button to engage different portions of the work.
3. In a machine of the class described, a 15 frame, sewing instrumentalities, a cloth plate, a button clamp, a member movable parallel to the surface of said cloth plate, and means for selectively connecting said button clamp to said member to move therewith or to said frame while maintained in operative relation to said sewing instrumentalities.
4. In a machine of the class described, a 20 frame, sewing instrumentalities, a cloth plate, a button clamp, a member movable parallel to the surface of said cloth plate, means for selectively connecting said button clamp to said member to move therewith or to said frame while maintained in operative relation to said instrumentalities, and means for moving said button clamp toward and from said cloth plate regardless of the position of said selective connecting means.
5. In a machine of the class described, a 25 cloth plate, a slide, a cam for reciprocating said slide, a second cam, means selectively connecting or disconnecting said cloth plate and slide, and means for selectively operatively connecting and disconnecting said cloth plate to and from said second cam.
6. In a machine of the class described, a 30 work plate, means for carrying a button, mechanism for fastening a button carried by said carrier to work on said plate, devices for relatively moving said button carrier and fastening mechanism to position fastenings through various holes in the button, mechanism for relatively moving said work plate and fastener mechanism to control the distribution of fastenings in the work, and means whereby said moving mechanism may 35 be rendered inoperative and said devices rendered operative to relatively move said fastener mechanism and work plate.
7. In a machine of the class described, a 40 work plate, means for carrying a button, mechanism for fastening a button carried by said carrier to work on said plate, devices for relatively moving said button carrier and fastening mechanism to position fastenings through various holes in the button, mecha- 45
- nism for relatively moving said work plate and fastener mechanism to control the distribution of fastenings in the work, means whereby said moving mechanism may be rendered inoperative and said devices rendered 50 operative to relatively move said fastener mechanism and work plate, and means for rendering said devices inoperative to relatively move said button carrier and fastener mechanism.
8. In a machine of the class described, a 55 button carrier, a work plate, mechanism for fastening a button carried by said carrier to work on said plate, means for moving said carrier and plate together relatively to said mechanism to cause fastenings to be applied through spaced pairs of holes in the button and into the work, and means for rendering said moving means inoperative to move said button carrier while remaining operative to move said work plate, whereby fastenings may be applied through a single pair of holes in the button and into the work at a plurality of spaced pairs of points.
9. In a machine of the class described, 60 members comprising a button carrier and a work plate, stitching mechanism for fastening a button carried by said carrier to work on said plate by stitches passing through a pair of holes in the button and into the work, and means for so moving said members and mechanism during the stitching operation as to lock the starting end of the stitching thread between the button and the work and thereafter to engage the thread in the work 65 at points distributed along parallel lengths thereof.
10. In a machine of the class described, a 65 machine frame, a cloth plate, a button clamp for holding a button adjacent work on said cloth plate, a member, means to reciprocate said member, means for coupling said work plate to said member, and means for selectively operatively connecting said button clamp and member or for fixing said button 70 clamp to said machine frame.
11. In a machine of the class described, a 75 cloth plate movable substantially parallel to the face of work placed thereagainst, a button clamp constructed and arranged to hold work on said cloth plate and relative to which said cloth plate moves, and a work engaging element carried by said button clamp and movable relatively thereto with the work as said work is moved by the movement of said cloth plate.
12. In a machine of the class described, a 80 cloth plate movable substantially parallel to the face of work held thereon, a button clamp movable toward and from work carried by said cloth plate and relative to which said cloth plate moves, and a work engaging foot arranged to press the work against said work plate, said foot having a resilient extension made fast to said button clamp and yieldable 85

to permit said foot to move with the work as said cloth plate is moved relatively to said clamp by said movement of said plate and movable with said clamp toward and from the work to press and release the work against and from said cloth plate.

13. In a machine of the class described, an article carrier, a work holder, sewing instrumentalities for sewing an article carried by 10 said carrier to work held by said holder, and means for automatically moving relatively to each other by successive increments said carrier, holder and instrumentalities during the sewing operation as to spread from each other 15 successive stitches engaging the article at one portion along a line in the work.

14. In a machine of the class described, a button carrier, a work holder, sewing instrumentalities for sewing a button carried by 20 said carrier to work held by said holder, and means for automatically moving relatively to each other by successive increments said carrier, holder and instrumentalities during the sewing operation in directions to spread 25 stitches passing through two holes in the button along lines in the work angularly related to the line of the said two holes in the button.

15. In a machine of the class described, a button carrier, a work holder, sewing instrumentalities for sewing a button carried by 30 said carrier to work held by said holder, and means for automatically moving relatively to each other by successive increments said carrier, holder and instrumentalities during the 35 sewing operation in directions to spread stitches passing through two holes in the button along lines in the work transverse to the line of the said two holes in the button.

16. In a machine of the class described, 40 sewing instrumentalities, a cloth plate, a button clamp for holding work against said plate and for holding a button in position to be sewed to the work and in operative relation to said instrumentalities, means for actuating said instrumentalities to cause stitches to be passed through a pair of holes in a button held by said clamp and into the work, and means for moving said cloth plate transversely to the line of said pair of holes while the 45 button is stationary to move the work correspondingly during the sewing operation to cause the stitches passed through the pair of holes in the button to be spread laterally in the work.

17. In a machine of the class described, 50 sewing instrumentalities including a needle, a cloth plate, a button clamp for holding work against said plate and for holding a button in position to be sewed to work on said plate and in operative relation to said needle, means for moving said needle relatively to the work and button to fix the button to the work by stitches lying in substantially parallel lines on the work, and means for moving 55 said cloth plate by successive increments at

an angle to the lines of stitches to move the work during the sewing operation while the button clamp is stationary to cause stitches engaging the same portions of the button to be distributed in the work laterally of their 70 lengths thereon.

18. In a machine of the class described, means for holding a button and work in position to fasten the button to the work, sewing instrumentalities for sewing the button to 75 the work with stitches arranged in substantially parallel lines relative to the work, and means for relatively moving the work and instrumentalities by successive increments laterally relatively to said lines during the 80 sewing operation to spread the stitches in the work.

19. In a machine of the class described, means for holding a button and work in position to fasten the button to the work, sewing 85 instrumentalities for sewing the button to the work, and means for moving the work relatively to the button and sewing instrumentalities by successive increments between 90 stitch formations to cause stitches engaging one portion of the button to engage a plurality of portions of the work.

20. In a machine of the class described, a button carrier, a work holder, sewing instrumentalities for sewing a button held by 95 said carrier to work held by said holder, and means for moving said work holder between successive stitching operations and while said button carrier is stationary.

21. In a machine of the class described, a button carrier, a work holder, sewing instrumentalities including a needle for sewing a button held by said carrier to work held by said holder, means for moving said needle laterally between successive stitching operations to cause the needle to pass alternately through each of a pair of holes in the button, and means for moving said work holder between successive stitching operations and while the button carrier is stationary to present different portions of the work successively in line with the holes of the button.

22. In a machine of the class described, a button carrier, a work holder, sewing instrumentalities including a needle for sewing a 115 button held by said carrier to work held by said holder, means for moving said needle laterally between successive stitching operations to cause the needle to pass alternately through each of a pair of holes in the button, and means for moving said work holder in a direction at an angle to the lateral motion of the needle between successive stitching operations and while the button carrier is stationary to present different portions of the work successively in line with the holes of the button.

In testimony whereof I have affixed my signature.

ROBERT L. LYONS.
